No. 14,635

Feb 5, 1884

8997

8997

UNITED STATES PATENT OFFICE.

CATHERINE SHIELS, OF NEW YORK, N. Y., ASSIGNOR TO THE BUTTERICK PUBLISHING COMPANY, (LIMITED,) OF SAME PLACE.

DESIGN FOR A GIRL'S CLOAK.

SPECIFICATION forming part of Design No. 14,635, dated February 5, 1864.

Application filed December 26, 1863. Term of patent 3½ years.

To all whom it may concern:

Be it known that I, CATHERINE SHIELS, of the city, county, and State of New York, have invented and produced a new and original Design for a Pattern of a Girl's Cloak, (numbered 8,997;) and I do hereby declare that the engraved prints accompanying this specification convey to any one accustomed to using paper patterns a clear understanding of how a garment made up by the pattern will appear.

The design shows double-breasted fronts displaying buttons all the way down, a half-fitting body-back exhibiting a full deeply-shirred

skirt attached upon its lower part, a cape that displays revers at its front edges, and a curved 15 notch at the center of the back, coat-sleeves, oblong pocket-laps, and a standing collar.

What I claim as my invention, and desire to secure by Letters Patent, is—

The design for a girl's cloak, as shown in 20 the engraved prints accompanying this specification.

CATHERINE SHIELS.
